CRUSHING DEVICE

Walter S. Clugston, Cambridge City, Ind.

Application February 15, 1937, Serial No. 125,942
Renewed May 15, 1939

1 Claim. (Cl. 83—12)

This invention relates to a crushing apparatus which is mainly designed for removing buttons from rags or the like, the general object of the invention being to provide two pairs of crushing rollers through which the rags are passed with adjustable yieldable means for pressing the rollers of one pair against the rollers of the other pair.

This invention also consists in certain other features of construction and in the combination and arrangement of the several parts to be hereininafter fully described, illustrated in the accompanying drawing and specifically pointed out in the appended claim.

15 In describing the invention in detail, reference will be had to the accompanying drawing wherein like characters denote like or corresponding parts throughout the several views, and in which:—

20 Figure 1 is a side view of the apparatus.
Figure 2 is a front view thereof.

In this drawing the numeral 7 indicates a base from which rises pairs of standards 8, 8a, and 9.

25 Rotatably supported between the pair of standards 9 are upper and lower rollers 5, and rotatably supported between the pair of standards 8a is an upper roller 4, and between the pair of standards 8 there is rotatably mounted a lower roller 3, the lower roller 3 supported between the pair of standards 8 being disposed in the same vertical plane with the roller 4 supported between the pair of standards 8a.

30 The standards 8, 8a are pivoted to the base 7 as at 10, and the rollers 3 and 4 associated with the standards 8, 8a are urged into peripheral contact with the rollers 5 associated with the standards 9 through the medium of suitable spring devices 11.

35 Also, the standards 9 at their upper ends are provided with angular or offset portions 12 to which may be connected conveying means for conveying the rags to a point where they will drop between the upper rollers 4 and 5, said conveying means not being shown though the upper 40 roller thereof would have its trunnions engaging

the slots 12' in the parts 12. A motor 24 is connected to one of the standards 9 and drives the lower roller 5 and sprocket means shown generally at 25 drives the upper roller 5 from the lower roller 5. Of course, the rollers 3 and 4 are driven from the rollers 5 by peripheral contact between the rollers and as will be understood when the rags pass downwardly between the two pairs of rollers the buttons on the rags will be crushed and thus removed from the rags. The rollers 5 may be toothed as shown or they may be plain. Each spring device includes a rod 26 having one end engaging an eye 27 carried by a standard 9, the rod passing through a hole in a pivoted standard and having its other end threaded to receive a nut 28 and a spring 11 encircles the rod and has one end bearing against a pivoted standard 5 and the other end against the nut.

Having thus described the invention, what is claimed as new is:

20 A crushing device of the class described comprising a base, a pair of stationary standards rising from the base, upper and lower rollers journaled in said standards and vertically spaced apart, means for rotating said rollers, a pair of aligned and spaced horizontal pivot members supported by the base and spaced from the stationary standards, a long standard and a short standard having their lower ends supported by each pivotal member for movement toward and away 25 from the stationary standards, a roller journaled 30 in the short standards and contacting the lower roller journaled in the stationary standards, a roller journaled in the long pivoted standards and contacting the upper roller journaled in the stationary standards, a rod pivoted to an intermediate part of each stationary standard and passing through the upper part of each short standard, a rod pivoted to an upper portion of each stationary standard and passing through an upper portion of each long standard, a spring on each 35 rod and a nut threaded on the free end of each rod and between which and a pivoted standard 40 the spring is located.

WALTER S. CLUGSTON.
